PRESS FOR CRUSHING CANS

John L. Ross, Cowan, Tenn.

Application April 15, 1938, Serial No. 202,349

1 Claim. (Cl. 153—10)

My invention relates to presses and more particularly to presses for crushing cans and the like driven by compressed air.

In recent years, it has become the practice in the auto and oil industry, to dispense lubricating oils from cans, usually of the quart size. The empty cans quickly accumulate at the garage or filling station and soon present the problem of housing or storing such cans. These empty cans are very light, consume a considerable space and make it impossible to accumulate in any reasonable space a sufficient weight of metal for salvage purposes. The expense of dispensing of the empty cans soon becomes appreciable.

Applicant with a knowledge of these problems has, as an object of his invention, the providing of a press which is operable from the ordinary compressed air apparatus maintained in the usual filling station and garage, for crushing said cans so that they may be stored in a small space.

In this way, a considerable weight of metal may be accumulated, time and expense of transporting the cans to a dump pile eliminated, and some salvage value realized therefrom.

I am aware that presses have been used in the prior art for various purposes. The old patent to Rymer, 38,606, discloses a hydraulic press utilizing a threaded piston and a nut mounted thereon for maintaining the piston in elevated position. Stucky, 212,823, shows another form of hydraulic press which is used for baling cotton while Pickett, 969,720, shows a press for compressing cans mounted on a vehicle and adapted to be driven through a gear mechanism responsive to the movement of the vehicle itself, or responsive to the invention or motor thereof.

The use of a hydraulic press for crushing cans would, of course, be out of the question. It would necessitate reservoirs for containing the fluid and pumps for forcing it into and out of the cylinder. The operation would be too slow and the power produced too great. There is also the problem of fluid leakage from the cylinder with its tendency to injure objects with which it comes into contact. Likewise, the use of the press of Pickett must always be in connection with a vehicle or engine. Furthermore, the use of a cylinder into which a can is to be inserted limits the size of the can, and prevents such can from spreading during the crushing operation, thereby resisting such crushing and increasing the power requirements of the press.

It is another object of applicant's invention to provide a press with a moving table mounted on a piston operable by compressed air. The piston

moves towards a stationary member and the can is interposed between the moving table and a stationary member and is crushed by engagement with them. The moving table and the stationary member are large and permit the can to spread as it is compressed. After the can is compressed, and the air pressure is released and the table is permitted to return to normal position by action of gravity. Applicant has, as another object of his invention, the provision of a press for crushing the can, then disengaging the chuck, releasing the air and allowing the moving table to fall back to normal position.

Other objects and advantages of my invention will appear from the following specification and accompanying drawing, and the novel features thereof will be particularly pointed out in the annexed claim.

In the drawing, Figure 1 is a side elevation in section of one form of my improved press. Figure 2 is a plan view, partly in section of the same press, taken along the line of 2—2 Figure 1.

Figure 3 is a detail of a portion of my improved press showing another form of valve for controlling the air supplied to the cylinder.

Referring to the drawing in detail, one designates a press upon which is mounted four rods which are attached to the press screw-threaded portions 23. A stationary member 3 is carried by the upper ends of rods 4. The reduced ends of these rods project through openings in the stationary member 3 permitting nuts 24 to be applied thereto, maintaining it against relative movement.

Disposed within said rods and projecting upwardly from press 1 is cylinder casing 5, which is preferably formed integral with such press. Within the casing 5 is a piston 7, having a packing element 8 of rubber, leather, or other appropriate material secured to the lower end thereof by means of a metal retainer or cup element 9 through which stud 10 passes and seats in a screw threaded socket in the piston 7. Seated in the other end of the piston 7 and secured thereto by screw threads, sweating or other appropriate means, is a piston rod 6 whose upper end is in turn seated in a movable table 2 having portions telescoped about the rods 4 and freely slideable thereon. The piston rod 6 may be secured to the table 2 by sweating, screw-threading, etc.

For the purpose of letting air into the cylinder, a bore 11 is formed in the base 1 and terminates the one edge of the base in a screw threaded outlook into which is inserted a plug 22. Leading into the bore 11 is a transverse opening which

is adapted to receive a tube 12. Mounted on one of the arms 4 of brackets 16 which carry rod 13, whose end terminates in a socket 17. The lower end of this socket or the socket in itself entirely 5 may be made of rubber or other appropriate material.

Seated in the socket 17 and rigidly mounted therein is a sleeve 19 whose upper end forms a valve seat. Disposed within the sleeve 19 is a 10 valve stem 18 having a T portion in its lower end and a valve at its upper end. Disposed about the stem, 18, is a coiled spring 20 for pressing the valve against its seat in the sleeve 19. Leading into the socket 17 is a tube 1 joining an air supply 15 or rubber hose 21.

Formed on the other end of the rod 13 is a handle 15. Interposed between the upper bracket 16 and the handle 15 is a coiled spring 14 which maintains the socket 17 from disengagement with 20 the tube 12.

The operation of the press is somewhat as follows:

The can to be crushed is set upon the moving table 2. The handle 15 is pressed downwardly 25 to overcome the force of the spring 14, bringing the T of the valve stem 18 into engagement with tube 12. This unseats the valve and permits air to flow through hose 21, socket 17, tube 12 and bore 11 to the cylinder casing 5. This air acts 30 upon the lower end of the piston 7 moving it upwardly to the dotted line position in Figure 1. The movement of piston 7 upwardly carries table 2 in the same direction causing the can to be engaged between stationary member 3 and moving table 2 exerting a force upon the can and 35 gradually crushing it as table 2 approaches stationary member 3. Before the table 2 reaches the dotted line in position of Figure 1 the can is crushed.

When this is accomplished, handle 15 is released and socket 17 is disengaged from tube 12 40 by the action of spring 14 which moves the rod 13 upwardly. This engagement of socket 17 from tube 12 permits spring 20 to return the valve to 45 its seat in sleeve 19, thereby blowing the air supply from hose 21.

The air in casing 5 is now permitted to flow out through bore 11 and tube 12, and the action of gravity returns the moving table to its normal position.

It is to be understood that the packing element 5 8 performs its usual function of preventing air from escaping around the valves of the piston 7 and, if it is desired, a cover may be applied to the upper end of cylinder casing 5 to close it.

In lieu of the chuck, applicant may substitute 10 a three way valve as shown in Figure 3. This is done by simply disconnecting tube 12 and substituting tube 12' therefor. The bracket 16, rod 13, socket 17, and other associated parts are dispensed with. The valve casing 25 is secured to 15 the tube 12' through a screw-threaded portion. The hose 21 is disconnected and a new hose 21' is screwed into or otherwise connected to the valve casing 25. When the valve is in the position shown in Figure 3 air passes through hose connection 21, passage 27 of valve 26 to and through tube 12'. This operates the piston. If the valve 26 is turned 90 degrees counterclockwise, the supply of air through hose 21' is blocked 20 and air from tube 12' flows through passage 28 into passage 27 and out port 29 of the valve casing. In this way, it is only necessary to turn the valve back and forth to connect and release the 25 air.

Having thus described my invention, I claim:

A press of the character described comprising 30 a base, a stationary member, standards projecting upwardly from the base for supporting the stationary member, a moving table interposed 35 between the base and stationary member, means for moving said table towards said stationary member including a cylinder carried by the base, a piston disposed within said cylinder, means for leading fluid to and away from the cylinder, a 40 valve resiliently mounted on one of said standards and movable into engagement with said fluid leading means to supply fluid to said cylinder to actuate said piston.

JOHN L. ROSS. 45
